NEEDLE PACKET

Norman Thomas Sanders, Mapleborough Green, near Studley, England, assignor to Coats & Clark Inc., New York, N.Y., a corporation of Delaware

Filed Sept. 27, 1962, Ser. No. 71,881

Term of patent 14 years

(Cl. D58—2)

FIG. 1 is a front elevational view of a needle packet showing my new design in closed condition;

FIG. 2 is a side elevational view thereof;

FIG. 3 is a rear elevational view; and

FIG. 4 is a perspective view thereof, in open condition.

The dominant features of my design reside in the portions shown in full lines.

I claim:

The ornamental design for a needle packet, as shown and described.
